ASPHALT SPREADER

John H. Trant, Jr., Norfolk, Va.

Application March 1, 1933, Serial No. 659,223

4 Claims. (Cl. 94—44)

This invention relates to new and useful improvements in road surfacing machines, and particularly to machines for laying and spreading surfacing materials, such as asphalt.

One object of the present invention is to provide a machine of this character by means of which surfacing material, such as asphalt, may be properly and efficiently comminuted, and then spread onto the surface of a road, to the desired depth.

Another object is to provide means by which the asphalt may be properly spread to the depth desired, and at the same time smoothed over the surface of the road to conform with the crown, or transverse curvature thereof.

A further object is to provide a device of this character which includes novel and efficient means for working the surfacing material across the road, and thinning out the edges thereof.

A further object is to provide a device of this character by means of which the above-named operations are carried on automatically, as the truck, which contains the supply of surfacing material, proceeds along the road.

Other objects and advantages will be apparent from the following description when taken in connection with the accompanying drawings.

In the drawings:

Figure 1 is a side elevation of the invention, shown attached to the rear end of a truck containing the surfacing material.

Figure 2 is a top plan view of the distributor; Figure 3 is a side elevation of the distributor.

Figure 4 is a vertical sectional view on the line 4—4 of Figure 2.

Figure 5 is a rear elevation of the distributor.

Figure 6 is a top plan view of the smoother and leveler.

Figure 7 is a side elevation of the smoother and leveler.

Figure 8 is an enlarged vertical sectional view on the line 8—8 of Figure 6.

Figure 9 is an enlarged vertical sectional view on the line 9—9 of Figure 6, showing the means for adjusting the leveling and scraping blades.

Figure 10 is a transverse sectional detail view on the line 10—10 of Figure 6.

Figure 11 is a vertical sectional view on the line 11—11 of Figure 10.

Figure 12 is an enlarged side elevation of a portion of the rear end of the smoother and leveler.

Figure 13 is a detail view showing the means for accomplishing the vertical adjustment of the frame of the smoother and leveler.

Figure 14 is an enlarged top plan view of a portion of the rear end of the smoother and leveler, showing the means for reciprocating the smoothing brushes.

Figure 15 is an enlarged rear elevation of a portion of the rear end of the smoother and leveler, also showing the brush reciprocating means.

Figure 16 is an enlarged vertical sectional view on the line 16—16 of Figure 6.

Referring particularly to the accompanying drawings, 10 represents a portion of a truck, which is adapted to contain the surfacing material, such as asphalt. Connected to the rear of the truck, by means of the links 11, is the spreader and distributor, represented as a whole by the numeral 12.

The distributor 12 consists of the end frames 13, each comprising the forwardly and rearwardly diverging legs 14, each of which legs is supported on a ground wheel 15, carried by an end of the axle 16, supported on the lower end of said legs, and extending transversely of said distributor. Transverse braces 17, connected at their opposite ends to the end frames, serve to hold the said frames in proper spaced relation. In the upper portion of the distributor is supported a hopper 18, having the upwardly extending mouth 19, into which material is shoveled, from the truck, while the lower portion of said hopper consists of a drum 20, extending transversely of the distributor frame. Mounted within the drum is a cylinder 21, the ends of the shaft 22, of which, are journaled in the end walls of said drum. Secured to the outer face of the cylinder, and radiating therefrom, are the pins 23, which cooperate with the rows of stationary pins 24, mounted within the drum, adjacent the lower discharge opening of the hopper. Mounted beneath the discharge opening of the hopper, and extending transversely of the distributor, is a downwardly and rearwardly inclined mouth 25, which receives the comminuted material from the hopper, and discharges the same onto the road surface.

Connected to the rear side of the distributor is the smoother and leveler, designated, as a whole, by the numeral 26. The smoother and leveler comprises a frame consisting of the longitudinal parallel beams 27, connected at their front and rear ends by the transversely extending bracing and spacing bars 28 and 29, respectively. Ex-

tending transversely of the intermediate portion of the frame 26, and journaled in bearings 30, on the side beams 27, is an axle 31, on each end of which, outside of the frame, is mounted a ground wheel 32. Each of the said bearings is adapted

60

80

85

90

95

100

105

110

to be raised and lowered by means of the adjusting screw 33, whereby to raise and lower the frame, with respect to the surface of the road.

- Extending diagonally between the side beams 5 27, from a point adjacent one end of the axle 31, to a point adjacent the opposite front corner of the frame, is a scraper blade 34, the intermediate portion of which is connected with a horizontal plate 35. Extending diagonally from the other 10 front corner of the frame, to said plate 35, is a short bracing strip 36, while a similar bracing strip 37, extends from said plate to a point adjacent the other end of the said axle. It will be noted that the rear end of the scraper blade 36 15 terminates a short distance from the side beam 27, whereby to provide an opening 36', between said blade end and the side beam, to permit the material scraped by said blade, to roll off said blade end and move rearwardly therefrom.
- 20 Rearwardly of the axle 31 is arranged a plate 38, similar to the plate 35, and secured to this plate are the inner ends of the short diagonal braces 39 and 40, extending respectively to a side beam 27, adjacent the outer end of the short brace 37, 25 and to the opposite rear corner of the frame. Extending from the other rear corner of the frame, diagonally to a point adjacent the other end of the scraper blade 36, is a scraper blade 41, the intermediate portion of which is connected, 30 with said plate 38. Extending transversely of the frame, and having their ends connected respectively to the plates 35 and 38, and to the side beams 27, are the braces 42 and 43. In the side beam 27, adjacent the outlet or rear end of the 35 scraper blade 41, is an opening 44, through which the material escapes, after having been scraped by said blade. Each of the scraper blades 36 and 41 is mounted in suitable guides, shown at 45, on the side beams 27, and adjustable vertically by means of the screws 46, whereby to regulate the position of said blades with respect to the surface of the material on the surface of the road. Secured at their ends to the forward ends 40 of the side beams 27, and extending transversely 45 of the frame 26, are the bars 47, to each of which are secured the downwardly extending spring raker teeth 48, for raking the surfacing material as the latter is deposited on the surface of the road.
- 50 Mounted on the rear ends of the side beams 27, and extending rearwardly therefrom, are the brackets 49. Mounted on each of these brackets 49, and extending in parallel relation to each other, in transverse arrangement across the 55 frame, are the depending guides 50. Slidable transversely of the frame, and supported in transverse pairs of said guides, are the heads 51 of elongated brushes 52, said brushes being adapted to engage with, and reciprocate across 60 the surface of the surfacing material, for the purpose of smoothing and leveling the same, as the machine proceeds along the road.
- 65 Mounted on one of the side beams 27, adjacent the rear end thereof, is a bearing bracket 53, which supports a short transverse shaft 54, having a bevel gear 55, on its inner end, and a sprocket wheel 56, on its outer end. Mounted on the rear transverse member 28, of the frame 26, is a similar bearing bracket 57, which supports a 70 transverse shaft 58, arranged at right angles to the shaft 54, said shaft 58 having a bevel gear 59, on its inner end, meshing with the bevel gear 55, and on its outer end a crank arm 60. Pivotedly connected with the crank arm 60 is one end of a 75 link 61, the other end of which is pivotally con-

nected with the intermediate portion of the inner brush head 51. Mounted on the intermediate portion of the member 28 is a rearwardly extending bracket 62, and pivotally connected centrally to this bracket is a rocker 63, one end of said rocker being pivotally connected with one brush head, while the other end is pivotally connected with the other brush head. Thus, as the shaft 58 is rotated by the shaft 54, the crank arm will cause the reciprocation of the inner brush, and through the connection of the rocker 63, between the two brushes, the other brush will be reciprocated, but in the opposite direction, and simultaneously with the reciprocations of the first brush.

80

85

90

On one end of the axle 31 is a sprocket wheel 64, and trained around this sprocket wheel, and the sprocket wheel 56, is a drive chain 65, by means of which motion is transmitted from the ground wheels 32, to the shaft 54, for the purpose of causing the reciprocation of the brushes 52.

95

Mounted on the intermediate portion of the front member 28, of the frame 26, is a small truck 66, which has a tongue 67, for attachment to the frame of hopper support. On the sides of the front ends of the beams 27 are the hooks 68, to which are connected the links 69, for connection with said hopper frame.

100

Mounted on the lower faces of the beams 27 are the runners 70, which support the frame 26, while traveling along the road, and between which the surfacing material is deposited.

105

Mounted on one side of the frame of the hopper supporting means is a motor 71, the shaft of which is connected with the shaft 22, of the cylinder 21, through the medium of the clutch 72, and the gear set 73.

110

In the operation of the invention, the parts being connected together, as shown in Figure 1, the truck 10 is driven along the portion of road 115 to be surfaced. As the mechanism proceeds, operatives, located in the truck 10 shovel the surfacing material into the mouth of the hopper, and the motor 71 being set in motion, the cylinder 21 will be rotated, whereby to properly comminute 120 the material, as it passes between said cylinder and concave, or stationary pins or teeth 24, to be discharged through the outlet 25, of the hopper, and deposited on the road. The material will thus be deposited in a layer which may have a 125 semi-uniform thickness, but conditions require that this material be leveled to a uniform thickness, and the surface thereon given a smooth appearance. To accomplish this is the purpose of the smoother and leveler. The rake teeth 48 pass through the upper portion of the surfacing material producing an approximately smooth surface, by spreading the material, as will be readily understood. The surface of the loose material is 130 then engaged and scraped by the forward scraping blade 36, and due to the fact that said blade is arranged diagonally across the frame portions of the material will travel along the blade and fall rearwardly from the open end thereof, to be 135 reengaged by the rear scraping blade 41, and caused to travel to the opposite side of the frame, where the excess of the material is discharged to the side of the road, through the outlet opening 44, in the side of the frame. As the machine 140 proceeds further, the reciprocating brushes 52 engage the surface of the new material, producing the smooth and level finish to the surfacing.

130

135

140

The guides 50 are vertically adjustable by means of the screws 50', carried by the brackets 150

49, so as to regulate the contact of the brushes 52, with the surfacing material.

What is claimed is:

1. A distributing and smoothing device for road surfacing material including a frame, oblique bars carried by the frame and extending in opposite directions with respect to their obliquity, a scraper blade supported on each of said bars, one of the blades having an end spaced from a side 5 of the frame and in proximity to one end of the other scraper blade, means for raising and lowering said blades on said bars, and the frame having a discharge opening at one end of said second blade.
- 10 2. A road surfacing machine including a frame, means carried by the frame for distributing material rearwardly and transversely thereof, brushes carried by the frame and mounted for reciprocal movement transversely thereof, means for reciprocating one of said brushes, and means connecting the brushes for transmitting an opposite reciprocating motion from said reciprocated brush to another of said brushes.
- 15 3. A road surfacing machine including a frame, means carried by the frame for distributing material rearwardly and transversely thereof, a ground engaging wheel connected to the frame, a

brush carried by the frame and mounted for reciprocal movement transversely thereof, means connected with the ground-engaging wheel and the brush for reciprocating the latter, a second brush mounted adjacent the first-mentioned brush for reciprocal movement, and a rocker carried by the frame and connected to the brushes for transmitting motion from the first mentioned brush to the second mentioned brush.

4. A road surfacing machine including a frame having an exit, oblique scrapers carried by the frame and extending in opposite directions with respect to their obliquity, one of said scrapers being adapted to guide scrapings to the other of said scrapers, and said other of said scrapers being adapted to guide scrapings to said exit, brushes carried by the frame and mounted for reciprocal movement, a ground-engaging wheel on the frame, a shaft on the frame, driving means connecting the shaft and wheel, a crank on the shaft, a pitman connecting the crank and a brush for reciprocating the latter, and a rocker carried by the frame and connecting the brushes whereby to transmit reciprocal motion from one brush to another brush.
